UNITED STATES PATENT OFFICE.

JAMES P. SCARTSARIS, OF WATERBURY, CONNECTICUT.

TRACK CONSTRUCTION.

1,302,977.

Specification of Letters Patent.

Patented May 6, 1919.

Application filed November 19, 1918. Serial No. 283,164.

To all whom it may concern:

Be it known that I, JAMES P. SCARTSARIS, a subject of the King of Greece, residing at Waterbury, in the county of New Haven and State of Connecticut, have invented new and useful Improvements in Track Constructions, of which the following is a specification.

This invention comprehends generally improvements in that class of inventions known as railway rails and joints and more particularly relates to an improved track construction.

It is the principal aim and object of the present invention to provide a device of the above mentioned character designed for supporting double flange wheels in such a manner as to prevent the wheels from jumping from the rails at the time rolling stock passes over the joints, frogs or switches of the track bed.

The invention has for an additional object to provide a device of the above mentioned character wherein plates of a novel configuration are employed at the meeting ends, curves, switches and crossing points of the rails of the track bed for preventing wheels from jumping the rails and for also preventing undue wear on the rail sections at such points by supporting the double flanges of the wheels thus reducing the bumping and knocking at the time the wheels pass such points.

Among the other aims and objects of this invention may be recited the provision of a device of the character described with a view to compactness, and in which the parts are few, the construction simple, the cost of production low and the efficiency high.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this connection that minor changes in the construction and arrangement of parts may be made without departing from the principles of operation of the various parts.

The invention is clearly illustrated in the accompanying drawings, in which:

Figure 1 is a top plan view of the straight section of the improved track showing the joint at the meeting ends of the adjacent sections.

Fig. 2 is a side elevation thereof.

Fig. 3 is a cross section on line 3—3 of Fig. 2.

Fig. 4 is a cross section on line 4—4 of Fig. 2.

Fig. 5 is a top plan view of the curved rail section.

Fig. 6 is a cross sectional view taken on line 6—6 of Fig. 5.

Fig. 7 is a top plan view of the improved track at a crossing point.

Fig. 8 is a bottom plan view thereof.

Fig. 9 is a cross sectional taken on line 9—9 of Fig. 7.

Fig. 10 is a top plan view of the switch frog forming part of the improved track construction.

Fig. 11 is a bottom plan view thereof.

Fig. 12 is a side elevation thereof, and

Fig. 13 is a cross section taken on line 13—13 of Fig. 10.

Fig. 14 is a detail sectional view of a portion of a double flange wheel for use in conjunction with the improved construction.

Similar characters of reference are employed in all of the above described views, to indicate corresponding parts.

Referring now, more particularly, to the accompanying drawings there is provided a pair of rail sections 1 and 2 the meeting ends of which are held in abutting and alining relation by a joint 3. The joint in this instance consists of opposed sections each comprising a horizontal base portion 4, a vertical web engaging portion 5 which at its point of juncture with the base portion 4 is provided with a longitudinal channel 6 for accommodating the base flanges of the rail sections and at the same time permitting of the base portion 4 being arranged beneath the base portions of the rails as indicated in Fig. 3. At this point it may be stated that the rail sections are of a conventional configuration but are being used in conjunction with the double flange wheel 7. Now in order to prevent the jumping of the wheel from the rails when passing over the meeting ends of the joints the upper edges of the

vertical portions are designed to project above the plane of the upper edges of the rail sections and are formed on their inner faces with grooves 8 for accommodating the 5 opposed flanges of the wheels of the rolling stock. In this connection it is to be observed that the flanges engage in grooves 8 at the time the tread portions engage the upper surfaces of the heads of the rail sections, 10 thus preventing knocking at the time rolling stock passes over the joints. Fastening bolts 8' are passed transversely through the vertical portions 5 and the web portions 1 and 2 of the rail sections for fastening the parts 15 in position. The joint, of course, is adapted to be anchored to the ties in any conventional manner.

Rail chairs generally designated by the 20 numeral 9 are employed and each is formed in complementary sections 10 designed to be positioned on opposite sides of one of the rail sections and anchored to the adjacent tie of the track bed as indicated in Figs. 1 to 4.

25 As intimated, to prevent jumping of the rolling stock from the track or rail at the curved section 11 thereof guard sections generally designated 12 are employed and are curved similarly to curved section 11 resembling a fish plate construction and configuration consisting of the web engaging portion 12 the upper edge of which lies above the plane of the upper edge of the rail section 11 and is cut away leaving a recess 14 30 on the inner edge and adjacent the head of the rail section 11, these rests or curves 14 lying, of course, on opposite sides of the head of the rail section 11 and accommodating the opposed flanges of the wheel 7. Tie 35 plates generally designated by the numeral 15 are employed for accommodating the rail section 11 and the guard sections 12, said tie plates being of a construction somewhat similar to the tie plate for the rail section 40 45 proper and consisting of opposed sections 16 each comprising a horizontal base portion 17 and an upright portion 18 shaped so as to conform to the outer face of the adjacent section 13. The base portions are notched 50 near their meeting ends as at 19 so that they may be readily fitted together beneath the rail section 11. Fastening bolts 18' are employed and are passed through the vertical portions 18, the guard sections 12 and the 55 web portion of the rail section 11 for fastening the parts together while the sections of the tie plate, of course, are adapted to be anchored to the ties in any conventional manner. As many of these tie plates 15 may 60 be employed as is found necessary, as is apparent.

In order that the wheels may pass over the crossing of the track a fragment of the crossing is illustrated in Fig. 7, consisting of rail 65 sections 20 formed at their point of inter-

section with grooves 21 which align with the opposing sides of the adjacent portion as indicated, said grooves being designed, of course, to accommodate the opposed flanges of the wheels 7. Coöoperating with these 70 grooves and projecting from the rail sections and preventing the wheels from jumping the rail section are the improved guard sections generally designated 22 each in the present instance being rightangular in plan 75 and angular in cross section comprising a base portion 23 fitted partially beneath the base of the rail and a vertical portion 24 projecting upwardly from the base portion 23 and integral therewith. In plan the vertical portion is as intimated rightangular in configuration and on the edge adjacent the rail sections is reduced providing grooves 25 for coöoperating with the adjacent portion of the rail section 20. The vertical portions, 80 of course, extend slightly above the plane of the upper surface of the rail section 20 providing a guard while the grooves 25 align with the grooves 21 and are designed to be engaged by the flanges of the wheels 7 at the 85 time the treads of the wheels engage the upper surface of the head or tread of the rail section. As is apparent, there are four of the guard sections 22 employed and the inner faces of the vertical portions are 90 designed to fit snugly against the adjacent faces of the web of the rail sections 20 as indicated in the drawings, being retained in position by suitable fastening bolts 26 which extend through the web portion of the rail 95 and the vertical portion of the sections 22 as indicated. As shown in the bottom plan view of the frog the horizontal base portions are formed on their meeting edges with interengaging notches 27 and tongues 28 for 100 assuring of the proper assembling of the sections 22 which, of course, are designed to be anchored in any conventional manner.

In Figs. 10 to 13, inclusive, there is illustrated a frog forming a part of the present 110 track construction, in the present instance consisting of a pair of rail sections 29 and 30 cast together and at an inclination with respect to each other. At the point of intersection and juncture of the rail sections the 115 heads thereof are formed with diagonally extending grooves 31 which align with the opposite sides of the adjacent section while fitted on opposite sides and beneath the point of juncture of the sections 29 and 30 120 are the opposed guard sections 32 each of which consists of a horizontal base portion 33 formed with a vertical portion 34. Each vertical portion is substantially V-shaped in plan and extends above the plane of the 125 heads of the rail sections being formed on their inner faces with recesses or grooves 35 which align with the grooves 31. Now in this connection it is to be observed that the double flanges of the wheels engage the op- 110

posed grooves at the time the treads of the wheels engage the upper surface of the heads of the rail sections 29 and 30 and prevent knocking of the wheels. The sections are 5 adapted to be anchored to one or more ties and are retained in position by means of bolts 36 which extend transversely through the vertical portions 34 and the web of the rail sections 29 and 30 at their point of junction.

10 It is believed in view of the foregoing description that a further detailed description of the operation of the invention is entirely unnecessary. Likewise it is believed that 15 the advantages of the invention will be readily apparent. However, in this connection it will be observed that there has been provided a track construction capable of being used in conjunction with double flange 20 wheels of rolling stock in such a manner as to peculiarly coöperate with the wheels for guarding the wheel at the time the rolling stock passes over the joints, crossings, frogs, curves, etc., and in addition serving to equalize 25 wear on the wheels and rail sections and obviating knocking when passing over the joints, etc.

As many changes could be made in the above construction and many apparently

widely different embodiments of this invention could be made without departing from the scope thereof it is intended that all matter contained in the above description or shown in the accompanying drawings shall be interpreted as illustrative and not in a limited sense. It is also to be understood that the language used in the following claim is intended to cover all the generic and specific features of the invention herein described and all statements of the scope of the invention which as a matter of language might be said to fall therein.

What is claimed is:

A track construction including in combination with crossing rail sections, members 45 comprising base portions for receiving and supporting the rail sections, and web engaging portions arranged perpendicular to the base portions and at right angles to each other, the upper edges of the web engaging 50 portions being positioned above the upper surfaces of the rail sections and formed with recesses on their inner faces for coöperating with the rail sections and providing grooves on opposite sides of the rail sections. 55

In testimony whereof I have affixed my signature.

JAMES P. SCARTSARIS.
